STAYBOLT AND METHOD OF MANUFACTUR-
ING THE SAME

William B. Peirce, Pittsburgh, and Nicholas J. Kouché, Bridgeville, Pa., assignors to Flannery Bolt Company, Bridgeville, Pa., a corporation of Delaware

Application May 11, 1936, Serial No. 79,026

5 Claims. (Cl. 10—27)

This invention relates to staybolts and their manufacture, and more particularly to the form and manufacture of what is known as a rigid staybolt with a square head.

5 The usual form of a finished rigid staybolt is a round bar or blank with a square head being used to hold the bolt during the threading operation and also used to screw the finished bolt in the boiler during the installation operation. As the 10 object of a staybolt is to support the outer and inner sheets of a boiler or to keep them from spreading under pressure it is obvious that it must be tightly screwed and riveted in the boiler sheets to prevent leakage and to have the necessary sustaining strength.

15 In order to make a staybolt fit neatly in the tapped holes of a boiler the threads must be accurately cut and perfect in shape, especially the tops of the threads must be fully formed. If, in the process of threading, a rigid staybolt is not held perfectly concentric with the threading dies, then the dies will cut too much off on one side and not leave enough material on the opposite side to make a full thread.

20 In the threading of a rigid staybolt where the thread must be perfect in shape right up to the square head it is necessary in commercial threading to hold the bolt on the square head. If the head is not concentric with the body then the 25 body will not be concentric with the die and the thread will not be perfect in form. A head that is non-concentric with the finished body of a rigid bolt has a tendency to wobble the bolt when it is being screwed in the boiler plates with a motor driven square socket. This wobbling sometimes 30 keeps the bolt from entering the second boiler sheet after screwing through the first sheet.

35 Heretofore in the manufacture of rigid staybolts it has been the usual practice to cut the commercial bar of staybolt iron into lengths and 40 then either hot forge or cold press the square on one end, and then thread the bolt its entire length by holding it by the square while the die cuts the thread. It is almost impossible to commercially 45 make a hot forged square on a bolt blank that is exactly concentric with the body, and the cold pressing of the square does not always make the squares concentric even if the dies are in perfect shape. In either hot forged or cold pressed 50 squaring a rough shoulder is left between the squared portion and the rest of the bolt which varies in length according to diameter of the bolt being squared. This rough shoulder is neither square nor round and is therefore a lost length as the thread cut on it is not fully formed.

Usually the size of the squares on all rigid staybolts are of the same size regardless of the diameter of the bolt. To make a good square of a standard dimension by the cold press process required a certain diameter of iron regardless of what diameter the bolt happens to be, then the end of all rigid bolts requiring a standard square should be the same or standard diameter regardless of the diameter of the body of the bolt. It is obvious that if this standard diameter to make a standard square is maintained for all diameters of bolts, the body diameter of large bolts must be reduced to this standard diameter for a length long enough to make the square. This has been customary practice, but usually is done by a separate operation.

55 According to the present invention, an annular kerf is cut into the blank stock at the time the blank stock is parted from the commercial bar on a parting machine. This kerf is a distance 60 from the end of the blank which allows just enough stock to make a good square. As the kerf is cut during the parting operation no extra time is required and when a forming or shaving tool is used between the parting and kerfing tool this portion of the bolt body may be reduced to the proper diameter to make a good standard square without any extra time over the parting operation. Both ends of the bolt blank may also be 65 chamfered by using a chamfering tool in combination with the parting, kerfing and forming tools without any loss of time. The kerf is ordinarily cut to a depth making its diameter equal or slightly under the flats of the square to be put on. This kerf leaves a clean-cut shoulder on the 70 body of the bolt capable of receiving a clean-cut 75 thread of full size, and an accurate termination of the thread of the bolt, also an accurate termination of the square end and its width is allowed 80 to be computed as part of the square length, thus 85 eliminating the lost length due to the rough shoulder made by the ordinary squaring process. When a bolt blank with a formed end of the proper size and a kerf cut to the proper depth at a proper distance from the end of the blank is 90 subjected to the squaring dies it produces a good 95 square, concentric with the body of the bolt. This then allows a perfect thread to be cut on the blank clear up to the kerf shoulder. By reason of the cutting kerf the cold working does not 100 extend back into the threaded section of the bolt.

The invention may readily be understood by reference to the accompanying drawing, in which:

Figure 1 indicates more or less diagrammatically the step in the process of manufacturing the 105

bolt wherein one length of stock is being cut off or parted from a rod while the next adjoining length of stock is having a kerf formed therein and the portion for the square formed to size.

5 Figure 2 is a side elevation of a portion of the blank showing the head end thereof in its proper shape.

Figure 3 is a similar view showing the blank after the head end had been squared.

10 Figure 4 is an end view of the completed bolt.

Figure 5 is a side elevation of the completed bolt.

Figure 6 is a side elevation of the head end of a slightly modified form of bolt.

15 Figure 7 is a perspective view illustrating one of two dies which are used in forming the square on the bolt.

Referring to Figure 1, A designates a piece of stock of indefinite length which is in the process 20 of being cut up into blanks. B indicates a blank which is almost cut off, the cutting tool for severing the blank B from the length of stock A being designated C. D represents a cutting tool maintained in predetermined spaced relation to cutter C for cutting a kerf in the stock A, a predetermined distance back from cutter C. F represents the portion of the bolt to be made into a square. If the diameter of the stock is such that the portion F has to be reduced to bring the diameter down to a diameter necessary to make a square head of standard size, a third cutter for 25 turning down the diameter of portion F may be provided between cutters C and D. In this cutting operation it may be assumed that the rod A is being turned by some suitable chuck not shown. After the blank B has been completely cut off the support E on which the cutters are carried is moved transversely away from the stock, the stock advanced the necessary length to form a 30 blank, and the operation is again repeated, the length of stock A thus being successively cut into blanks, each blank when it is completed having a portion for a head and a kerf formed therein a predetermined distance from one end thereof, 35 such head portion also being reduced where necessary.

This is clearly illustrated in Figure 2 wherein the blank B has a kerf designated 2 therein, a head forming portion 3 between the kerf and the 40 end of the blank. In this figure, as distinguished from Fig. 1, we have shown the head portion reduced in diameter to the extent necessary to form a good square head of standard dimension. The body of the blank is designated 4. The body 45 has the original diameter of the stock A while the portion 3 is, as is usually the case, of smaller diameter. The kerf 2 is of such depth that the diameter of the neck portion 5 connecting the body 4 with the portion 3 is substantially the 50 same or slightly less than the flats of the square head which is subsequently formed.

If the blank shown in Figure 2 has the head forming portion 3 formed into a square by being pressed between two dies as shown in Figure 7, 55 the body portion 4 being laid in the semi-circular part of the die 7 and the head forming portion 3 in the square part of the die then the formed blank, as shown in Figure 3, will be produced. This die is of the type now generally used in the 60 manufacture of staybolts, and forms no part of the present invention per se. The square head thus formed by being pressed between two dies as shown in Figure 7 is more perfectly formed on a blank with a kerf for the reason that the metal 65 is allowed to flow longitudinally in both directions

and as the portion that is to be squared is of the proper diameter regardless of the diameter of the body, the square made therefrom is as nearly perfect as can commercially be made, and as the squaring die does not have to shear the body 5 diameter of the bolt down to the square size, the concentrating and alignment is more easily maintained.

Figure 3 clearly illustrates a blank that has been squared, showing the square shoulder made 10 by the kerf, while Figure 4 shows an end view of the same bolt.

Figure 5 shows the side elevation of a finished bolt showing the clean-cut threads right up to the shoulder made by the kerf and also that the 15 length of the square can be computed from this shoulder. To install a rigid staybolt in a boiler it first must be screwed through both boiler sheets and just enough of the threaded portion left to project past the face of the sheet to rivet over. 20 The riveting process upsets the bolt in its threaded hole and forms a slight button head that seals the joint between the bolt and the boiler sheet. It is obvious then that the square head must be removed after the bolt is screwed in place, the 25 square then having served its full function. The removal of the square head is sometimes done by breaking it off, and in such cases it is sometimes desirable to facilitate the breaking by what is commonly known as necking in or nicking the 30 head. This is illustrated in Figure 6 where the neck portion 8 is of less diameter than the thickness of the head portion 9 and the threaded body of the bolt 10. This neck is sufficiently strong to withstand the torque of both threading the bolt 35 and of screwing it into place, but facilitates the severing of the head after the bolt has been screwed into place. This extra deep kerf can be cut in the same way as the standard depth of kerf and does not require any more time or 40 expense.

By the practice of the present invention, bolts of better appearance and greater accuracy are produced. All of them are of uniform appearance and all have a full thread up to the kerf. The 45 head forming is effected with less distortion of the metal, and the effect of cold working is confined to the head and does not extend into the body of the bolt. Less work has to be performed by the dies, so that the operation is performed 50 more easily and with less wear on the dies. The method, moreover, enables the blank to be initially a fraction of an inch shorter than with methods heretofore employed, and this results in a further economy to the manufacturer.

We claim:

1. The method of forming a staybolt which comprises forming a blank of round metal stock, producing an annular kerf in said stock adjacent one end thereof thereby dividing the blank 60 into a body portion and a head portion connected by an intervening neck portion of reduced diameter, and subsequently forging the head portion to produce a square head having a diameter less than the diameter of the body 65 portion and subsequently threading the body portion of the blank.

2. The method of making staybolts which comprises producing a blank of round metal stock having a kerf therein adjacent one end thereof, said kerf dividing the blank into a body portion and a head-forming portion connected by a neck portion of reduced diameter, and subsequently pressing the head-forming portion of the blank to a square shape the transverse 75

thickness of which is not substantially less than the diameter of the neck portion.

3. The method of making staybolts which comprises producing a blank of round metal stock having a kerf therein adjacent one end thereof, said kerf dividing the blank into a body portion and a head-forming portion connected by a neck portion of reduced diameter, and subsequently pressing the head-forming portion of the blank to a square shape the thickness of which is somewhat greater than the diameter of the neck portion.

4. In the manufacture of staybolts from a length of round stock, the steps which comprise simultaneously cutting the stock into lengths and forming on each length an annular kerf near one end of the blank whereby the blank is divided

into a body portion and a head-forming portion connected by a neck portion of smaller diameter than the body or head portion, pressing the head-forming portion to a substantially square cross-section the thickness of which is substantially less than the outside diameter of the body portion, and thereafter threading the body portion.

5. A staybolt comprising a threaded body portion, a forged head portion and a circular neck portion connecting the head and body portions, said neck portion being of less diameter than the threaded body portion and having substantially the original grain of the metal blank from which the bolt is formed.
